UNITED STATES PATENT OFFICE

WILLIAM S. FORREST, OF CHICAGO, ILLINOIS

ICE-CREAM AND CONFECTIONERY CONTAINER

Application filed June 15, 1929. Serial No. 371,103.

This invention has particular relation to an article of manufacture in the nature of a container or package for ice-cream confections and edibles such as pop corn, peanuts, 5 and other sweetmeats.

The package or container is spherical and generally simulates a baseball in appearance. The spherical construction makes the dispensing of the package or article in crowds, 10 such as at baseball stands, an easy matter, since the vendor is enabled to pitch the package to the customer with more or less accuracy. By providing the package with coin slots the vendor is enabled to safely deliver the required change along with the 15 package by inserting coins through the slots into pockets provided for that purpose.

In carrying out the invention I provide a spherical casing formed of a plurality of 20 sections secured together. These sections are filled or partially filled with ice-cream or confections and are then sealed together by pasting thereon a pair of gores or cover sections to form a shell similar to the cover sections 25 of a baseball. The sealed sections or gores are ornamented by representations such as stitches stamped or otherwise formed on the gores, thereby giving the finished package the appearance of a base-ball.

30 A particular object of the invention is the provision of a container for edibles or sweetmeats which simulates a baseball.

Another object of the invention is the provision of an improved container for edibles 35 which is capable of being sealed and thereby to preserve the contents in a sanitary condition.

A still further object of the invention is the provision of a sanitary container for edibles 40 of the class described which is provided with coin receptacles whereby the delivery of change from the vendor to the vendee is easily accomplished.

The invention has among its other objects 45 the production of a container of the kind described which is simple in construction, convenient, durable, reliable, and satisfactory for use wherever found applicable.

Many other objects and advantages of the 50 construction herein shown and described will

be obvious to those skilled in the art from the disclosure herein given.

To this end my invention consists in the novel construction, arrangement and combination of parts herein shown and described, 55 and more particularly pointed out in the claims.

In the drawings, wherein like reference characters indicate like or corresponding 60 parts;

Fig. 1 is a view of the device as it appears when assembled and sealed for dispensing; and

Fig. 2 is a section along the line 2—2 of 65 Fig. 1, drawn to a larger scale.

In the drawings I have shown a preferred form of the invention embodied in a casing or container having two equal hemispherical sections secured together, but it is to be understood that the number and relative sizes 70 of such sections may be varied and that the invention is limited in the number and sizes of such sections only to the extent indicated in the appended claims.

The improved container is designated generally by the reference character 10, and is shown as comprising a relatively thick inner casing covered by a thin outer casing. The inner casing comprises upper and lower hemispherical sections 11 and 12, respectively. 75 The casing may be constructed of pasteboard or of any other suitable material. The section 11 has an outer flange 13 which overlaps a corresponding inner flange 14 formed on the section 12. The flanges 13 and 14 are 80 constructed to fit closely and thereby secure the upper and lower sections 11 and 12 together.

The lower section 12 may contain a quantity of ice-cream which has been deposited 85 therein preferably by the use of a device customarily used for filling ice-cream cones.

After depositing the cream in the lower section 12, the upper section 11 is then pressed 90 into position substantially sealing the contents from contact with the atmosphere. The upper section 11 may also be separately filled with ice-cream before placing the sections 11 and 12 together or, if desired, the cream 95 may be molded into a sphere which has the 100

same diameter as the container. Any other confection may be placed in the container, if desired.

A pair of gores or the like 17 and 18, preferably formed from relatively thin tough paper, are next pasted over the inner casing, the gore 17 being arranged symmetrically about and longitudinally of the line joining the upper and lower sections 11 and 12. Both 10 of the gore sections 17 and 18 are cut in the usual form for baseball covers and each has a coating 29 of adhesive material on its inner surface by means of which the gores are pasted onto the sections 11 and 12. The gores 15 17 and 18 are cut so as to have their adjoining edges in close contact, thereby simulating the appearance of a baseball. The outer peripheral edges of the gores 17 and 18 are ornamented by representations stamped 20 thereon such as a plurality of stitches 28, thereby still further giving the package the appearance of a baseball.

A plurality of recesses are formed in the outer surface of the sections 11 and 12 to provide 25 coin pockets after the gores 17 and 18 are pasted thereon. A recess in the section 11 forms a pocket 19 into which a coin may be inserted through a slot 22 formed in the gore 18. A coin 25 is shown partially inserted through the slot 22 into the pocket 19. A similar recess in the gore 18 provides a pocket 20 into which a coin is partially inserted through a slot 23 formed in the gore 18. Similarly still another recess provides 30 a pocket 21 for a coin 27 which is partially inserted in the pocket through a slot 24 in the gore 18. The recesses are so located in the sections 11 and 12 that the slots 22, 23 and 24 will respectively register with one 35 edge thereof to form pockets open at one end. I have shown a 5-cent coin as inserted in the pocket 19, and a dime inserted in the pockets 20 and 21 respectively. It is obvious that any number of coin receptacles of the kind 40 described may be provided to make change for a dollar, a half-dollar, or a quarter which the purchaser may toss to the vendor. If the purchaser happens to be at some distance from the vendor the latter usually has difficulty 45 in making safe delivery of the change to the purchaser. With my device the vendor may insert the proper change in the various pockets and toss the ball to the purchaser, making the exchange an easy and rapid transaction without danger of loss.

The confection may be eaten by first breaking, cutting, or tearing the outer gore coverings 17 and 18 and then separating the sections 11 and 12. A spoon or the like of 50 any suitable material may, if desired, have its handle inserted in a slot in one of the gore sections 17 or 18 for the convenience of the purchaser. Nuts, candy, or any other edible may be dispensed in this manner.

Having thus described my invention, it is

obvious that various immaterial modifications may be made in the same without departing from the spirit of my invention; hence I do not wish to be understood as limiting myself to the exact form, construction, arrangement and combination of parts herein shown and described, or uses mentioned.

What I claim as new and desire to secure by Letters Patent is:

1. As an article of manufacture, a spherical container comprising two substantially identical sections, a shell closely fitting and covering said container, a layer of adhesive material operable to fasten the shell to the container, said shell comprising two similar gore sections, and means simulating stitches on the contiguous edges of said gore sections, the wall of said container having a recess forming a coin receptacle and the casing having a slit adjacent said recess through which a coin may be inserted into the receptacle. 75

2. As an article of manufacture, a spherical container comprising two substantially identical hemispherical sections, overlapping flanges forming the abutting portion of said sections, a shell covering for the container comprising two similar gore sections each symmetrical about its longitudinal and transverse axes, a layer of adhesive material operable to fasten the shell on the container, a longitudinal axis of one gore section and the transverse axis of the other substantially coinciding with the juncture line of said container sections, the wall of said container having a recess forming a coin receptacle and the casing having a slit adjacent said recess through which a coin may be inserted into the receptacle. 90

In witness whereof, I hereunto subscribe my name this 12th day of June A. D. 1929.

WILLIAM S. FORREST.
